(57) CLAIM

The ornamental design for a combination fireplace, fountain, music player and planter, as shown and described.

DESCRIPTION

FIG. 1 is a front elevation view of a combination fireplace, fountain, music player and planter showing my new design; FIG. 2 is a right side view, the opposite side being a mirror image thereof;

FIG. 3 is a top view thereof; and,

FIG. 4 is a perspective view thereof.

The broken line showing of parts of the drawings is included for the purpose of illustrating use and environment and forms no part of the claimed design.
